Primary Examiner — Susan Bennett Hattan*Assistant Examiner* — Leanne Was-Englehart(74) *Attorney, Agent, or Firm* — Seed IP Law Group LLP**(57) CLAIM**

The ornamental design for a fence panel, as shown and described.

DESCRIPTION

FIG. 1 is an isometric view of a fence panel, showing one embodiment of my new design.

FIG. 2 is a front elevational view thereof.

FIG. 3 is a rear elevational view thereof.

FIG. 4 is a cross-sectional view thereof taken along line 4-4 in FIG. 2.

FIG. 5 is a cross-sectional view thereof taken along line 5-5 in FIG. 2; and,

FIG. 6 is a front elevational view of a fence panel, showing another embodiment of my new design comprising horizontal and vertical break lines. The area between the break lines forms no part of the claimed design. All other views are consistent with FIGS. 1 and 3-5.

Stippling shown in the drawings is intended to represent the three-dimensional contours of the design, and are not intended to indicate surface decoration. The broken lines in the figures depict portions of the fence panel that form no part of the claimed design.
